UNITED STATES PATENT OFFICE.

CLARE W. BANTA, OF SAN FRANCISCO, CALIFORNIA.

DEPOSIT SAFE.

Application filed November 27, 1925. Serial No. 71,604.

This invention relates to deposit-receiving apparatus particularly for use in connection with commercial and savings banks. As is well known, the larger banks today provide 5 branch banks throughout the community for the convenience of their depositors, the depositors being permitted to make their deposits at the most convenient branch. While this custom or system is an improvement 10 and convenience over the old system of a single bank in each community, it yet leaves some things to be desired. I propose to provide an even greater distribution of deposit stations and so locate such stations that a 15 depositor can deposit his salary or wages substantially as soon as he receives the same and before he has had an opportunity or temptation to spend all or a part thereof. Such a system therefore not only operates 20 as a great convenience to the public, but also encourages the habit of thrift.

Each branch bank in operation today requires the services of several employees and is expensive to operate. It is the primary 25 object of my invention herein to provide a deposit-receiving apparatus which will be adapted to safely and securely receive the deposits and require the services of only one attendant. The expense of such a deposit- 30 ing station will be small and therefore permit of a wide distribution of such stations throughout each community. With one or more of such stations located in each factory, office building, or other place of business, 35 having a number of employees, such employees will have the convenience and incentive of a bank directly at the place of business and where they receive their salary or wages.

40 It will furthermore be understood that my invention is applicable to use in stores and offices wherein the cash receipts can be deposited hourly, twice daily, or before and after banking hours, without the necessity 45 of going to the bank. The invention is also applicable to banks for the purpose of reducing the number of receiving tellers necessary. A deposit receiving apparatus of the type disclosed herein can be placed adjacent 50 each receiving teller and the teller's time saved and any waiting on the part of the depositor eliminated, since the depositor can merely drop his deposit into the apparatus and receive a temporary receipt therefor. 55 It will furthermore be noted that the apparatus as illustrated is entirely portable,

whereby the same can be easily moved from place to place as may be desired, for inculcating thrift or as an advertising feature.

The construction and operation of the apparatus disclosed herein for carrying out 60 this system is hereinafter more fully described.

In the accompanying drawing I have 65 illustrated one specific embodiment of my invention, but it will be understood that the invention can be otherwise embodied and that the drawing is not to be construed as defining or limiting the scope of the invention, the claims appended to this specification 70 being relied upon for that purpose.

Referring to the figures of the drawing: 75 Figure 1 is a vertical sectional view through a deposit-receiving apparatus comprising my invention.

Figure 2 is a perspective view thereof partially broken away.

Referring more specifically to the drawing by reference characters, 1 indicates a safe or vault having the usual chamber 2 80 therein closed by a door 3. Deposits are adapted to be made into the safe through a chute 4 leading thereto from a hopper 5. It will be understood that this chute can be mounted in any manner desired and that 85 means to be hereinafter described are provided for quickly closing the chute in a manner protecting the contents of the safe against fire or theft.

As illustrated, I mount a turret 6 on the 90 safe to rotate on the axis of a post 7. This turret carries the portion 4^a of the chute 4, which is adapted to cooperate with the portion 4^b in the safe. Mounted on the turret is a member 8 carrying the hopper 5. The 95 member 8 can be rotated on a post 9 to bring the hopper into or out of alignment with the chute 4^a. In the drawing, the parts are shown in the deposit-receiving position, a bag 10 being placed in the safe and held 100 open by hook brackets 11 and a baffle plate 12 preferably being provided to deflect the deposits into the bag.

In the apparatus illustrated, the turret 105 provides a means for quickly closing the chute in case of fire or attempted theft. A smaller chamber is provided within the chamber 2 and an electric motor 14 therein is operatively connected to rotate the turret through a worm and worm wheel connection 15 and 110 post 7. A switch 16 conveniently placed outside the safe, is in the circuit 17 to the

motor. The closing of the switch is adapted to rotate the turret 180°, bringing the chute portion 4^a out of alignment with the chute 4^b. The worm and worm wheel connection 5 would ordinarily prevent manual backward movement of the turret to the original position. I however preferably provide other locking means for positively preventing any unauthorized backward rotation of the 10 turret.

A locking bolt 18 within the safe is normally held in contact with the bottom of the turret by a spring 19. When the turret rotates to the inoperative position, this bolt 15 moves into a depression 20 in the turret and securely locks the turret against movement. It will be noted that the bolt being entirely in the safe can only be released by opening the door 3. It will furthermore 20 be noted that the bolt carries a switch contact plate 21 of a switch in the motor circuit. When the bolt is in the position illustrated, the switch is closed, but when the bolt is moved to the turret locking position, 25 the switch is automatically opened in a manner breaking the circuit to the motor. This switch also being entirely within the safe, cannot be closed without opening the door 3. The bottom wall 22 of the turret will 30 preferably be made relatively thick as illustrated, to provide greater protection to the safe over and about the chute 4^b.

I also preferably provide means for locking the member 8 in either of its two positions. This means comprises a spring-pressed locking bolt 23 adapted to engage in either of two depressions 24 in the top of the turret. The bolt can be released by a cam 25 on a post 26, the cam extending 40 beneath the bolt and the post being adapted to receive a key 27.

One manner of using my invention is substantially as follows. The apparatus with one attendant is stationed at the factory or 45 other business place to be accommodated, as many of such stations being established in different factories or within different parts of the same factory, as seems best. A representative of the bank calls in the morning 50 before any deposits are made and places the bag 10 in the safe and locks the door 3, the turret being left in the position illustrated. The one attendant in charge, who has the key to the lock 26, but who does not 55 know the combination of door 3, places the member 8 in the position illustrated.

Each depositor himself places his deposit in a container, marks the container and drops the same into the hopper 5, the attendant giving him a temporary receipt therefor. At intervals during the day and 60 at the close of business the bank armored car calls at the several stations and the collector opens the door 3 and carries the deposits to the bank.

In case of fire or should the attendant be held up by attempted robbery, he closes the switch 16 merely by a slight movement of his foot, this being possible even though his hands are held upwardly. The motor thereupon rotates the turret to the locking position above defined, in which position the heavy turret bottom 22 fully protects the chute 4^b in the safe. 70

The attendant can at any time disconnect 75 the hopper from the chute by releasing the lock bolt 23 and rotating the member 8. This would be desirable when leaving the station for any period of time, even if there were no deposits in the safe, in order to 80 be assured that nothing will be dropped into the safe.

I desire it to be understood that one of the most important uses for my deposit safe is the having of one of such safes at a central point where commercial depositors of a bank who are located at some distance from the office of the bank can go to make 85 their deposits. These deposit safes can be located in various business sections of the city and all the depositors of the bank who are located in the vicinity of these sections can make their commercial deposits daily through the medium of this deposit safe, rather than having to come to the main office 95 of the bank. Every few hours an armored collecting car will go to these safe deposit stations and bring the deposits thereof to the main office of the bank. Thus the use 100 of my invention will be a great aid and convenience to commercial banks and their customers.

Having thus described my invention, what I claim is:

1. A portable deposit receiving apparatus 105 comprising the combination with a safe, of a chute leading thereinto, a movable member cooperating with the safe and carrying one portion of the chute, power operated means for moving the member to carry the said one portion of the chute out of alignment with the chute portion in the safe, and means for setting the power operated means into operation.

2. A portable deposit receiving apparatus 115 comprising the combination with a safe, of a chute leading thereinto, a movable member cooperating with the safe and carrying one portion of the chute, power operated means for moving the member to carry the said one portion of the chute out of alignment with the chute portion in the safe, means for setting the power operated means into operation, and means for locking the member in the said moved position. 120

3. A portable deposit receiving apparatus 125 comprising the combination with a safe, of a chute leading thereinto, means for quickly closing the chute in a manner protecting the contents of the safe, an electric 130

motor for operating said means, a switch for the motor, means within the safe for locking the apparatus in the closed chute position, and means cooperating with the last named means for breaking the motor circuit when the locking means functions to lock.

4. A portable deposit receiving apparatus

comprising the combination with a safe, of a chute leading thereinto, a turret rotatably mounted on the safe and carrying one portion of the chute, power operated means for rotating the turret to a position closing the chute, and means for setting the power operated means into operation.

CLARE W. BANTA.
